SAFETY LIFE SAVING FENDER FOR CARS

Filed Dec. 14, 1926

2 Sheets-Sheet 2

JOHN TUBA,
of Julian Witten

UNITED STATES PATENT OFFICE.

JOHN TUBA, OF WHITING, INDIANA.

SAFETY LIFE-SAVING FENDER FOR CARS.

Application filed December 14, 1926. Serial No. 154,776.

This invention relates to life saving fenders adapted to be attached to the front of street cars, automotive busses, trucks, pleasure automobiles, and the like.

5 The principal object is to provide a fender which is automatic in its effective operation.

Another object is to provide means whereby when the fender is struck by a person 10 it will automatically carry him back, out of danger.

15 Features of the construction are found in a fixed basket adjustably supported by brackets secured to both sides of a street car, or automobile. Under this fixed basket is supported in stirrups or rack bars, an auxiliary basket or endless apron of rubber or other suitable material to protect the person struck from injury.

20 This apron is in turn supported on long rolls extending across the track or roadway to nearly the width of the upper fixed basket.

The lower basket is normally held in its 25 retracted inoperative position by latch devices which are automatically released when a trip bar is struck by a body and forced back a short distance by slide bars ranging backwardly in guides under the fixed basket, said slide bars being formed with the trip bar and movable therewith.

The front portion of the lower basket has small wheels and is normally supported 30 above the ground, but is permitted to drop, causing said wheels to contact with the ground when the trip bar is forced back.

The trip bar and its slide bars collectively constitute a trip frame.

35 Long spiral springs are mounted at the back of the fender on rods connected to a cross rod or bar on which the rear apron roll rotates. The rods are connected at opposite ends of said roll at opposite sides of the structure and are extended rearwardly 40 into and through dash pots or cushioning cylinders and have pistons.

The cylinders each have a by pass and contain oil so that when the lower basket or apron is released, the action of the spring 45 will force said basket forward to pick up the person struck and convey his body upwardly and backwardly into the fixed basket.

50 A quick forward thrust of the apron is prevented by the oil being slowly forced forwardly ahead of the pistons through

the by passes and in back of the pistons as will be understood.

The parts of the life saving fender may be returned to the normal inoperative position from the platform of the car or from 60 within an automobile by pull rope or chains, or by other suitable methods and devices, such as by one or more rack bars connected by gears to shafting and operating by a hand wheel, crank or the like.

65 The parts of the device may be protected from dust and dirt by suitable housings or casings and are also well padded with rubber or other soft, elastic and waterproof material so that the person struck will not be 70 unduly injured.

75 For the accomplishment of these and such further objects as will be apparent to those skilled in the art to which this invention appertains, the invention consists of the following construction, combination and arrangement of parts hereinafter specifically set forth and illustrated in the accompanying drawings forming a part thereof, wherein is shown an illustrative embodiment 80 of the invention, but it will be understood that such changes, variations and modifications may be resorted to as fall within the scope of the claims hereunto appended.

In the drawings:—

85 Fig. 1 is a side elevation of the improved life saving fender attached in position on a street car platform.

Fig. 2 is a plan view of the device detached from the car platform with parts of 90 the construction broken away.

Fig. 3 is a detail side view of the lower basket or apron.

Fig. 4 is a section thereof.

Fig. 5 is a detail perspective of parts of 95 the construction.

Fig. 6 is an enlarged partial section taken on the line 6—6 of Fig. 1.

Referring to the drawings by characters of reference, I show at 10 a fixed basket 100 11 of a street car by brackets 12 having slots 13 through which bolts 14 are passed and clamped.

Carried on the under side of fixed basket 105 10, at opposite sides thereof, are rack bars 15, on which flanged gears 16 are mounted in rolling contact. These gears are keyed to the ends of a cross shaft 17, on which a long roller 18 is loosely mounted and to 110

which gear wheels 19 are keyed. These gear wheels are in constant mesh with similar gears 20, keyed on short pins 21, which enter the ends of an apron drive roller 22, and are 5 locked to rotate therewith.

The rollers 18 and 22 are tied together by end plates 23 (see Fig. 5) in which are bearing openings 24 for the shaft 17 and the pins 21.

10 Supported by the rack bars 15, through the gears 16, are side arms 25, of a lower basket or endless apron 26, carried at the rear by the roller 22, and at the front on a roller 27 revoluble on a cross shaft 28, having wheels 15 29 on its ends to engage the road bed when a person is struck.

15 Mounted in guide blocks 30, on the sides of the fixed basket, are parallel arms 31, connected at the front by a bumper bar 32, preferably thickly padded with rubber or other soft material 33 to protect the person when picked up by the safety fender.

20 The plates 23, connected to the opposite sides of the lower basket or apron at the rear thereof, are formed with inwardly directed angular extensions 34, to which piston rods 35 are riveted or otherwise secured, as at 36.

25 Projecting from under the rear corners of the fixed basket frame, are backwardly ranging horizontal brackets 37 on which are pivoted at their angles, bell crank catches 38, the catch portions 39 normally engaging keepers 40 in the plates 23, through the action 35 of springs 37^a, to retain the lower basket in its retracted back position against the forward urge of spiral springs 41, carried by the piston rods 35, between the portions 34, of the plates 23 and the forward ends 40 of dash pots 42, provided with by-passes 43, through which the contained oil or other liquid is forced by the reciprocating movements of pistons 44.

30 When a body strikes the bumper bar 32, it and its side bars 31 are forced backward against the pulling action of springs 45 (which normally hold these parts in the forward position), until said bar strikes the front of the fixed basket, and when in this 45 position, lock sockets 46, in the side bars 31, are under the locking noses of hinged dogs 47, which may be lifted by pull cords or wires 48, operated by a handle 49, above the car platform.

35 When drawn back to its inoperative position (Fig. 1) the lower basket is held up under the upper basket by inwardly directed lugs 56', on the rack bars 15, engaging bevelled lugs 57' on the side bars 25 thereof.

40 The rear roller 18 of the lower basket is divided midway its length to make space for a strap 50 which encircles the cross bar 17, and to which is attached a pull rope or wire 51, after which it is passed backwardly 45 around a pulley 52 supported in a bracket 53,

and thence upwardly to a drum or other winding device 54, operated by a crank or handle 55. The drum may be placed in any convenient position on the car or automobile, inside or out. 70

The spring 41, when the parts are released by the side bars 31 releasing the catches 39, are designed to force the lower basket forwardly and as this movement starts, the forward wheels of the said basket will drop to 75 the ground and by reason of the rolling engagement of the gears 16, with their racks 15 the top reach of the apron 26 will be moved upwardly and backwardly thus carrying a prostrate person rearwardly into the 80 fixed basket 10, out of danger.

The forward movement of the spring pushed lower basket is not violently rapid but has a somewhat retarded travel caused by the holding action of the dash pot 42. 85

At the time the apron frame starts forward, a projection 56 breaks contact between spring terminals 57 of the electric circuit 58, controlling a car or automobile to bring it to a quick stop, as will be understood. 90

The pull ropes or wires 48 and 51 are for re-setting the parts of the life saving fender when a person is struck or should the parts be accidentally tripped by contact with another car, a pole, fence, or other object. 95

I claim:

1. In a life saving fender for vehicles, a rigidly supported basket having guide blocks at the sides thereof, a frame slidable in said blocks and comprising side arms 100 and a bumper bar connecting them at the front, an auxiliary basket positioned under the rigid basket, and means controlled by the movements of said frame for releasing said auxiliary basket and for forcing it 105 forwardly for the purpose set forth.

2. A life saving fender for vehicles comprising a fixed basket attached to the front of the vehicle, an auxiliary basket having wheels at the front and movably supported 110 under the fixed one, means for automatically moving the auxiliary basket forward with its front wheels resting on the road bed when a person is struck, and means for returning the parts to the normal back position, said means comprising pivoted latches and dash pot controlled springs to retard the forward thrust thereof. 115

3. In a life saving fender a main basket 120 rigidly supported at the front of a vehicle and having guides at the sides thereof, a bumper frame supported therein and consisting of side parallel arms and a connecting bumper bar at the front and normally 125 spaced from said basket said bar being padded with soft material, tensional means connected to the side arms and to a fixed point to normally urge the bumper frame forwardly, an auxiliary basket, and means 130

controlled by said frame for forcing it forwardly into the operative position.

4. In a life saving fender a rigidly mounted basket, an auxiliary basket comprising side bars carrying leveled lugs, front and rear rollers, an endless apron on said rollers, wheels at the front thereof and gears at the rear, a bumper frame slidable on said fixed basket, means controlled by the said frame for pushing the auxiliary basket forward, and means for rotating said gears to operate the apron as the said auxiliary basket is moving forward.

5. A life saving fender including a main basket and an auxiliary basket normally supported thereunder, a bumper frame and means controlled by said frame for forcing the auxiliary frame forwardly from under the main basket, said means comprising swinging catches, plunger rods, springs thereon, and dash pots to retard the forward movement of the parts.

6. A life saving fender for cars, comprising a main basket having a rigid bar frame, cushioning material on and mesh material between said bars, brackets having adjustable connections with said basket and bolted to the car, an auxiliary basket

mounted under the main basket, a bumper frame slidable on said main basket, devices controlled by said frame for forcing the auxiliary basket forward with its front end resting on the ground, and connections operated from the front of the car for returning said auxiliary basket to its normal inoperative position.

7. In a life saving fender a rigidly mounted basket, an auxiliary basket comprising side bars carrying beveled lugs, front and rear shafts connecting said side bars, gears keyed to the rear shaft, a roller thereon, a roller and wheels on the front shaft, an endless apron carried by the front roller and the said driving roller, means for maintaining the two rear rollers in fixed relation, rack bars arranged along and under the side edges of the fixed basket and with which the said gears are meshed, a bumper frame slidably supported in said fixed basket, and means controlled by said frame for forcing the auxiliary frame forwardly for the purpose set forth.

Signed at Whiting, in the county of Lake, and State of Indiana, this 21st day of May, A. D. 1927.

JOHN TUBA.
